UNITED STATES PATENT OFFICE

2,511,055

DEVICE TO SHARPEN TWIST DRILLS

Joseph Ganz, Zurich, Switzerland

Application April 13, 1946, Serial No. 661,938
In Switzerland April 13, 1945

3 Claims. (Cl. 51--219)

1

The present invention relates to a new and improved device for sharpening twist drills by grinding.

The main object of the invention consists in the provision of a device by means of which the points of twist drills may be re-sharpened even by unexperienced workmen in such a manner that the cutting edges are truly symmetrically arranged with reference to the axis of the twist drill and that the backing-off is effected in a predetermined measure.

In the accompanying drawings an embodiment of my invention is shown by way of an example.

Fig. 1 shows part of the twist-drill-grinding machine in a perspective view.

Fig. 2 is a side elevation of the device seen in the direction of the arrow A part being shown in section on line II--II of Fig. 4.

Fig. 3 illustrates part of the device in a side elevation.

Fig. 4 is a cross-section taken on line IV--IV of Fig. 2.

Fig. 5 shows parts of the device in a top view parts being shown in section on line V--V of Fig. 2.

Figs. 6, 7 and 8 are cross-sections taken on lines VI--VI of Fig. 5, on line VII--VII of Fig. 4 and on line VIII--VIII of Fig. 5 respectively.

Fig. 9 shows in a side elevation a clamp to hold the drill.

Fig. 10 illustrates the position of the tip of the drill with reference to the grinding disk while it is in its grinding position.

Fig. 11 is a face view of the drill and of the shield controlling the position of the drill.

Figs. 12 and 13 are face views of the drill arranged in its holder.

Fig. 14 is a section taken on line XIV--XIV of Fig. 2.

The same numbers of reference relate to like parts in all the figures.

In the base of an electric motor 1, driving the grinding disk 2, a bar 4 is arranged running parallel with reference to the driving shaft 3 of the motor 1. On the bar 4 a device is adjustably mounted for holding and guiding the twist drill B which is to be re-sharpened on the cylindrical working face F of the grinding disk 2. Said device comprises an arm 5 mounted on said bar 4. The arm 5 is fixed in its working position by a hand operated clamping screw 6. The free end of arm 5 is provided on each side with a groove 7, said grooves, running parallel to each other in a direction at a right angle to the shaft 3. The bottom wall of the grooves 7 is provided with a slot 8 extending transversely through the arm 5. In one of the said grooves 7 a slide 11 is arranged

2

slidably adjustably, said slide 11 may be operated and adjusted in its position by a screw threaded spindle 9 with an operating knob 10. The slide 11 may be fixed in its position in the arm 5 by a nut 12 on a pin 111 extending through the slot 8.

The slide 11 is carried on one end of the cylindrical pin 111 the other end of which carries a device for truing the working face F of the disk 2.

10 A collar formed integrally on the pin 111 between the ends thereof is slidably seated in the other groove 7 on the arm 5 as shown in Figs. 3, 4 and 7. As shown in Fig. 7 the collar has two flat faces preventing a rotation of the pin 111 in the groove 15 7. The device and its operation is known per se and is not shown in the drawings. On the slide 11 a sleeve 13 is arranged in which an upright trunnion 14 is rotatably mounted. On the trunnion 14 a head piece 15 is fastened in which a short horizontal shaft 161 is rotatably mounted. The shaft 161 carries at its face a conical pin 17 which serves to aid the adjustment of the head piece 15 with reference to the working face F of the grinding disk 2. To the shaft 161 an angular connecting piece 16 is fastened which carries a bar 18.

The axis Z--Z of the bar 18 is at an obtuse angle with reference to the axis Y--Y of the shaft 161. The bar 18 may be turned about its axis Z--Z, in the angular connecting piece 16 and

30 may be fixed in its position by a set screw 56. The adjusting of the axis of the bar 18 and therewith of the cutting edges of the twist drill with reference to the working face F of the grinding disk 2 is illustrated in Figs. 12 and 13. The angle over which the bar 18 may be turned may be limited by a stud 22 (Fig. 8) to obviate any damaging of the adjusting device by the grinding disk 2. In the bar 18 a longitudinal groove 23 is provided adapted to receive the drill to be sharpened.

35 The groove 23 is formed by two walls 24, 25 standing at an angle to each other the line of intersection of the walls 24, 25 being in the axis of the bar 18. On the bar 18 an annular slide 20 is adjustably mounted. The slide 20 may be fixed 40 on the bar 18 by means of gripping members 26 pressed on the bar 18 by means of a nut 27 having a conical face. The slide 26 is provided with a screw-threaded portion on which a nut 32 is mounted, on which a coiled spring acts to take up the play. The nut 32 is provided with an inwardly projecting tooth 36 engaging an annular groove in a slide 34 which serves as an abutment for the drill to be sharpened. The slide 34 engages the 45 groove 23 of the bar 18. The nut 32 serves for the fine adjustment of the drill in its axial direction, a marking 38 on the nut facilitates the cor-

rect setting of the drill-abutment 32, 34 and therewith of the point of the drill with reference to the working face F of the grinding disk 2. The point of the conical pin 17 on the shaft 161 is used for adjusting the position of the drill with reference to the grinding face of the disk 2 as the latter is being reduced in diameter while doing work. At the inner end of the bar 18 an abutment 41 is arranged engaging one of the flutes of the drill to secure the proper position of the cutting edges of the drill arranged in the groove 23 of the bar 18. The abutment 41 facilitates the positioning of the drill and its turning about 180 degrees to work the point of the drill quite symmetrically. The set screw 43 engaging a groove 46 of the pin 14 limits the movement of the bar 18 and therewith that of the point of the drill towards the working face of the grinding disk 2. By an adjustment of the set screw 43 the conicity of the point of the drill may be varied. To retain the drills, even those of small diameter, in the groove 23 of the bar 18 an auxiliary clamp 48 might be used. The clamp comprises a bar 49 and a blade spring 50 fixed together at one end. By means of a nut 51 and of a screw threaded bolt passing through bores of bar 49 and spring 50 the drill to be sharpened is held securely on the bar 18. The bar 18 is provided with a radial bore 18^a suitably tapped for receiving a mounting pin 52 on the bar 49 (Figs. 1 and 9).

The use and operation of the device is as follows:

To sharpen a drill B the latter is placed into the groove 23 of the bar 18 and is secured therein by the clamp 48. The drill is arranged to abut on the member 41. The drill being axially displaced by the adjusting device 20. The bar 18 is swung against the working face F of the grinding disk 2 about the axis of the trunnion 14, which movement is limited by the set screw 43 and the point of the drill is shaped first on one side by grinding, the bar 18 and therewith the drill being moved up and down about the axis y—y. If one side of the point of the drill B is ground to its proper shape the bar 18 with the drill B is moved away from the grinding face of the disk 2. The drill B is turned about 180 degrees about its axis and again fastened in the bar 18 whereupon the point of the drill B is again brought to bear on the working face F of the disk 2. The axes of all the drills of different diameters are all in a common plane S—S (Figs. 12, 13) symmetrically to which the walls 24, 25 are placed. The plane S—S is inclined at an angle α to the horizontal. The angle α is adjustable by loosening the set screw 56 and then rotatably adjusting the bar 18 about the axis z—z after which adjustment the set screw 56 is again tightened. The angle α corresponds to the desired backing-off angle and is indicated by the scale 38. As shown in Figs. 11 and 12 for twist drills of any diameter the same angles are produced at a certain fixed position of the bar 18.

To attain full symmetrical faces of the point of the drill it is necessary that the drill be advanced equally towards the grinding disk in both of its grinding positions and that the drill be turned exactly 180 degrees.

What I wish to secure by U. S. Letters Patent is:

1. In a grinding device for twist drills, the combination, a grinding disc rotatable about a fixed axis and presenting a peripheral grinding face, a supporting bar arranged parallel to said fixed axis, a support carried by said bar and having thereon a slide adapted to be moved at right

angles to said fixed axis, means for securing said slide in the desired position, a head piece rotatably mounted about a vertical axis on said slide, a horizontal shaft rotatably mounted in said head piece and provided at one end with an angular connecting piece to which is secured a drill-receiving bar in such a manner that the longitudinal axis of said bar forms an obtuse angle with said horizontal shaft, said drill receiving bar comprising a cylindrical rod having a longitudinal groove formed of angularly positioned plane walls for receiving the drill to be ground, said angular connecting piece being provided with means for rotatably adjusting said cylindrical rod with respect thereto, whereby the backing-off angle of the drill is changed, and means on said bar for positioning the end of the drill to be ground relative to the peripheral grinding face of said grinding disc.

2. In a grinding device for twist drills, the combination, a grinding disc rotatable about a fixed axis and presenting a peripheral grinding face, a supporting bar arranged parallel to said fixed axis, a laterally extending arm carried by said bar and having mounted on its outer edge a slide adapted to be moved at right angles to said fixed axis, means for securing said slide in the desired position, a head piece rotatably mounted about a vertical axis on said slide, means for limiting the rotative movement of said head piece to a predetermined and adjustable angle, a horizontal shaft rotatably mounted in said head piece and provided at one end with an angular connecting piece to which is secured a drill-receiving bar in such a manner that the longitudinal axis of said bar forms an obtuse angle with said horizontal shaft, means for limiting the rotative movement of said horizontal shaft to a predetermined angle, said drill receiving bar comprising a cylindrical rod having a longitudinal groove formed of angularly positioned plane walls for receiving the drill to be ground, said angular connecting piece being provided with means for rotatably adjusting said cylindrical rod with respect thereto, whereby the backing-off angle of the drill may be changed, and means on said bar for positioning the end of the drill to be ground relative to the peripheral grinding face of said grinding disc.

3. A grinding device according to claim 1, in combination with a holder comprising a detachable clamping device adapted to retain the drill to be ground in the groove of said cylindrical rod, said holder including a bar for engaging said rod and a leaf spring engaging said drill and urging the same into said groove.
